(57) **CLAIM**

The ornamental design for a router plane, as shown and described.

DESCRIPTION

FIG. 1 is a perspective view of a router plane of the present invention showing my new design.

FIG. 2 is a top plan view of a router plane shown in FIG. 1.

FIG. 3 is a bottom plan view of a router plane shown in FIG. 1.

FIG. 4 is a left side elevation view of a router plane shown in FIG. 1, the right side elevation view being identical thereto.

FIG. 5 is a front end elevation view of a router plane shown in FIG. 1; and,

FIG. 6 is a back end elevation view of a router plane shown in FIG. 1.

The broken line in FIG. 6 illustrates an unclaimed portion of the claimed design.
